United States Patent Office

Des. 177,596
Patented May 1, 1956

177,596

FINGER RING

Ronald F. Silver, St. Paul, Minn.

Application September 13, 1955, Serial No. 37,913

Term of patent 14 years

(Cl. D45—10)

Fig. 1

Fig. 2

Fig. 3

Fig. 4

Figure 1 is a perspective view of a finger ring, showing my new design;

Figure 2 is a front elevational view thereof;

Figure 3 is a side elevational view thereof; and

Figure 4 is a top plan view of the same.

I claim:

The ornamental design for a finger ring, as shown.
